MAGNETRON DISCHARGE TUBE CIRCUIT

Waldemar Ilberg, Berlin, Germany, assignor to
 Telefunken Gesellschaft für Drahtlose Tele-
 graphie m. b. H., Berlin, Germany, a corpora-
 tion of Germany

Application December 16, 1937, Serial No. 180,103
 In Germany December 30, 1936

3 Claims. (Cl. 179—171.5)

This invention relates to circuits for the stabilization of the discharge action in magnetron tubes. There is an annoying effect frequently met with in the operation of magnetron transmitters, that when, for instance, the load changes or when unusually high modulation peaks occur, the oscillations become interrupted and must be restored by artificial means either through temporary adjustment of the magnetic field or through change of the operating potentials. In this specification a circuit principle is disclosed which overcomes the aforementioned undesirable effect and assures operating stability of the magnetron discharge tube. In addition, and as a result of circuits based on this invention, it is possible to obtain a better linear modulation characteristic giving a straight line over a wider range.

One method aiming at the stabilization of magnetron generators is set forth in German Patent 476,404 (issued May 16, 1929) which shows additional windings alongside the main magnet winding. The additional windings may be energized by the total emission current. The resulting magnetic field has its intensity regulated to maintain the negative resistance of the discharge path and thereby the frequency of the generated oscillations at a constant value. Such circuits do not admit a high degree of modulation, and besides are practically dependent upon an electrically excited main magnetic field.

This invention deals with circuits which may be used, if desired, for frequency modulation. The magnetron tube can be worked, if need be, with a permanent magnet whose field intensity is not easily varied by electrical means. Nor is it necessary to use all of the discharge current for stabilization inasmuch as the current of a portion of the discharge path is sufficient.

The distinguishing feature of the circuit based on this invention is that the current of a portion of the discharge path is caused to act preferably on the bias potentials of the electrodes in such a manner as to avoid an interruption of oscillations and thus to give a better modulation characteristic.

For the carrying out of this idea magnetron tubes are used with several positively biased electrodes and the partial discharge current from one electrode is put through a resistance to obtain a voltage drop. These resistances should be predominantly of ohmic nature while their shape or form is immaterial. They may be independent of temperature variations if required or else may have compensating positive and negative tem-

perature coefficients. If it is required that these resistances respond very quickly to any change of current or potential, it is preferable to use glow tubes as negative resistances. The potentials appearing across the resistance will be additive to or subtractive from the biasing potential of the same electrode or that of another electrode group.

My invention will now be explained in more detail by reference to the accompanying drawing, in which:

Figure 1 shows diagrammatically a novel circuit arrangement for a magnetron discharge tube as used in my invention;

Fig. 2 shows a modification of both the circuit and the magnetron tube, the latter being provided with auxiliary electrodes; and

Fig. 3 shows still another modification of the circuit arrangement.

In Fig. 1 is illustrated a split anode magnetron tube in cross section. The anodes A₁ and A₂ are connected across an oscillating circuit C, L' and L''. At the point of junction of the two inductances L' and L'' is inserted a condenser 3, the capacitance of which acts as a short circuit for high frequencies and at the same time serves the purpose of blocking the different direct current plate potentials.

From one side of the condenser 3 there is a direct lead to the positive terminal of the anode potential source 4. From the opposite side of this condenser is connected a resistance 5 leading to said potential source. The negative terminal of the direct current source 4 is connected to the cathode K. The discharge space is contained in an envelope R. A source of modulating potentials M is preferably coupled through a transformer 6 to the circuit leading from the source 4 to the two anodes A₁ and A₂ by way of the inductances L' and L'' respectively.

In Fig. 2 a magnetron is shown with a one piece anode 7 and auxiliary electrodes 8 and 9. Corresponding elements of this circuit and of the circuit of Fig. 1 are given like references. In the anode power lead is inserted an ohmic resistance 5 which, if necessary, can be shunted by the condenser 10 which does not offer any appreciable resistance to either the modulation or the high frequencies. The leads of the two auxiliary electrodes 8 and 9 are connected across the resistance 5. An axially directed electrostatic field which is set up between the auxiliary electrodes 8—9 and the cathode K varies according to the magnitude of the anode current. In this variable crossfield the electron paths are somewhat de-

flected. Thus the electron paths are not perpendicular to the cathode but are more or less spiraled with their axis inclined towards the cathode. The result thereof is that a break in the oscillations is avoided.

Fig. 3 shows a cross sectional view of a magnetron tube having an outer screen or protective electrode N and a plurality of inner anodes A₁ and A₂. Under normal conditions the outer electrode N is at highest positive potential with respect to cathode K. Under these assumptions one side of the bias voltage source 4 is common to all electrodes. The anode current is fed from source 4 through a resistance 12 having a negative temperature coefficient. This resistance, therefore, becomes lower when the total anode current increases. The external electrode N is positively biased with respect to the direct current potential applied to the anodes A₁—A₂, the increased potential being supplied by a battery or other source 13. Materials such as "Urani dioxide" and "Thyrite" can be employed in making resistors with a negative temperature coefficient. Such resistors resemble porcelain and consist of admixtures of conductive and non-conductive particles, where the latter predominates.

The basic idea of the invention is not limited to the herein illustrated and described examples. Its realization can be carried out in a variety of ways. For instance, especially in the case of electrically excited magnetic fields a portion of the anode current can be used in an amplifying sense by means of a supplemental winding in the magnetic field exciting system. Normally, then, the operating points are so chosen, that only a part of the electron stream reaches the anode, the remaining electrons being spiraled by the deflecting magnetic field. In the event that the anode voltage should be lowered, under the known normal operating conditions there would be a danger of interruption of the oscillations because of the insufficient number of electrons reaching the anode. In a circuit arrangement of my invention a reduction of anode current is necessarily accompanied by a reduction in the result-

ing magnetic field. There will be less spiraling of electron paths and a condition similar to the normal will continue to prevail. It is to be understood that the idea of the invention is not limited to transmitters but can be applied also to receivers, especially of the heterodyne type.

I claim:

1. A circuit arrangement including an electron discharge tube having a cylindrical anode, a linear cathode within the anode, end-plates adjacent the extremities of the anode, and magnetic field exciting means for controlling the emission paths in said tube, sources of operating potentials applied between the cathode and anode, said sources including direct current potentials and modulating potentials, a connection having negligible resistance from the positive side of the direct current source to one of said end-plates and a circuit including a predominantly ohmic resistor connected from said direct current source to the other of said end-plates, and to said anode, said resistor constituting self-biasing means applicable to one of said end plates and operable in dependence upon its own conductance for insuring stable operation of said tube.

2. A circuit arrangement according to claim 1 wherein said resistor possesses a negative temperature coefficient.

3. In a circuit arrangement comprising an electron discharge tube having a cathode, a cylindrical anode surrounding the cathode, and a plurality of end plate electrodes, a magnetic field exciting means for controlling the course of electrons in the discharge space between the cathode and the anode, means including a resistor for applying unlike direct current potentials to different ones of said end plate electrodes, and a modulating source connected in circuit between said cathode, said direct current source, said resistor and said anode; said modulating source being operative to render said resistor effective to vary the potential difference between said end plate electrodes.
